UNITED STATES PATENT OFFICE.

CHARLES D. SEEBERGER, OF NEW YORK, N. Y., ASSIGNOR TO OTIS ELEVATOR COMPANY, A CORPORATION OF NEW JERSEY.

CONVEYER SYSTEM.

1,095,361.

Specification of Letters Patent.

Patented May 5, 1914.

Application filed July 19, 1907, Serial No. 384,534. Renewed August 19, 1910. Serial No. 577,996.

To all whom it may concern:

Be it known that I, CHARLES D. SEEBERGER, a citizen of the United States, residing at New York, in the county of New York and State of New York, have invented certain new and useful Improvements in Conveyer Systems, of which the following is a specification, reference being had therein to the accompanying drawings.

10 This invention relates to improvements in conveyer systems, such as moving footways, adapted to provide transporting ascending and descending runs between successive levels.

15 One of the objects of the invention is to provide a system comprising a plurality of duplex conveyers in which each conveyer provides oppositely moving runs between successive floors or levels and each pair provides ascending and descending runs between adjacent floors or levels.

20 The invention also contemplates a system of duplex conveyers in which the ascending and descending runs between adjacent levels are on opposite sides of a median line and the ascending run to one level is alined vertically with the descending run to such level.

25 Other objects of the present invention will be apparent from the disclosure of its several features.

30 The invention consists of the organization and arrangement of parts hereinafter particularly described and then pointed out in the appended claims.

35 In the accompanying drawings—Figure 1 is a diagrammatic view of my system of duplex conveyers providing ascending and descending runs between five floors or 40 levels; Fig. 2 is a diagrammatic plan view from the second floor, portions being broken away for convenience in illustrating the arrangement of the runs; and Fig. 3 is a diagrammatic view showing my invention providing ascending and descending runs between seven floors or levels, the series of runs on opposite sides of a median line being moved apart bodily lengthwise in order to show each duplex conveyer individually.

45 In Fig. 1 where the system of duplex conveyers is adapted to five levels, 1, 2, 3, 4, and 5 indicate the floors of a building or successive levels of any other structure. In Fig. 3 the system is extended to include seven

levels and the two upper floors are designated 6 and 7.

55 A traveling conveyer 8, such as a moving footway or traveling stairway, has an entrance landing 9 at floor 1 and then travels on an incline, as at 10 to an exit landing 11 at floor 2. From the landing 11 the conveyer passes upwardly, as at 12, through a carriage 13, extending between floors 2 and 3, and then extends as an entrance landing 14 at floor 3, continuing, as at 15, to provide 60 a descending run which terminates in an exit landing 16 at floor 2. From the landing 16 the conveyer passes downward, as at 17, through a carriage 18 between floors 1 and 2 to the landing 9. By this arrangement it 65 will be seen that the continuous conveyer 8 provides oppositely moving runs between successive levels, that is to say, the ascending run 10 connects the first and second or intermediate levels and the descending run 70 75 15 connects the third and second or intermediate levels. The exit landings 11 and 16 of the ascending and descending runs 10 and 15, respectively, are at the same intermediate level, while such ascending and descending runs have their entrance landings at the different levels with which they respectively connect. The ascending and descending runs of the conveyer are in the same vertical plane, and by extending the 80 85 conveyer between three floors both its ascending and descending portions are utilized to provide transportation, although such runs travel in opposite directions and connect successive pairs of floors.

90 In order that there may be transporting runs moving in opposite directions between each pair of floors or levels, for descending as well as ascending, I employ a second conveyer which is identical with that heretofore described, except that it is turned around or arranged reversely, as shown in Figs. 1 and 3. The second conveyer 19 provides an entrance landing 20 at floor 2, an inclined transporting run 21 to the third floor, an 95 exit landing 22 at the third floor, whence it passes, as at 23, through a carriage 24 to the second floor where it forms an entrance landing 25. It then descends by the inclined run 26 to an exit landing 27 at floor 1 and 100 finally passes upwardly, as at 28, through a carriage 29 to the landing 20.

105 The conveyers 8 and 19 are preferably

arranged side by side, as shown in Fig. 2, upon the common transverse line A—B of Fig. 3. As shown in Fig. 3, the exit landing 11 of the ascending run 10 is at the same level as the entrance landing 20 of the ascending run 21, while the exit landing 16 of the descending run 15 is at the same level as the entrance landing 25 of the descending run 26, all of such landings being at the common intermediate level, and arranged in opposite pairs as shown in Fig. 2. From this it is apparent that when the passenger is carried up the incline 10 to floor 2 and wishes to continue on to floor 3 he has to merely step from the landing 11 to the landing 20, Figs. 2 and 3. In descending the passenger, in the event that he desires to continue on from floor 3 to floor 1, when he reaches the landing 16 steps upon the landing 25 and is carried to the lower level.

It is obvious from the foregoing that by employing a pair of oppositely moving conveyers, each communicating with three floors or levels and transporting on its ascending and descending runs, I am able to accommodate or provide for continuous transportation in either direction between three floors by only two straightaway machines, whereby the number of machines required for such service is reduced one-half without in any manner reducing the carrying capacity or curtailing the service. With these machines arranged on opposite sides of a median line, as shown in Fig. 2, the exit and entrance landings at each level will be in line with each other and will be disposed in pairs, so that a passenger may pass directly from one to the other at any intermediate landing when traveling in either direction.

It is obvious that the invention may be extended to provide for higher levels by duplicating the arrangement shown and described to the extent necessary, and that in such case each pair of conveyers will serve three floors and at each intermediate level or floor the exit and entrance landings in each direction will be opposite or in pairs, so that when the machines are arranged upon the common transverse line A—B, Fig. 3, passengers may readily pass from one to the other in substantially continuous travel between any or all levels in either direction. The system thus extended is shown in Figs. 1 and 3, where 30 and 31 indicate, respectively, the ascending and descending runs of a conveyer 32 which is similar to the conveyer 8 and located over the same. A conveyer 33 providing an ascending run 34 and a descending run 35 is located over the conveyer 19 and opposite the conveyer 32 in the same manner that the pair 8 and 19 are arranged. The oppositely moving runs 30 and 35 connect the third and fourth floors, while the oppositely mov-

ing runs 31 and 34 connect the fourth and fifth floors. The entrance and exit landings of the conveyers 32 and 33 are arranged in the same manner as those of the conveyers 8 and 19. As will be apparent from Figs. 1 and 3, if it is desired to continue up from floor 3 to floor 5, the passenger need only step from the exit landing 22 of run 21 to the entrance landing of the ascending run 30 which is opposite thereto and when at the top of the run 30 he steps from the exit landing of the conveyer 32 to the entrance landing of the ascending run 34 of the conveyer 33; and to descend from floor 5 the passenger on alighting from the exit landing of the descending run 31 of conveyer 32 steps to the entrance landing of the descending run 35 of the conveyer 33 and then from the exit landing of such conveyer across to the entrance landing 14 of the descending run 15 of conveyer 8, completing the descent to floor 1 by the descending run 26 of conveyer 19.

In Fig. 3 the system is shown as extended to seven floors. The conveyer 36 corresponds to conveyers 8 and 32 and has its runs 37 and 38 in vertical alinement with the runs 10, 15, 30 and 31, and the conveyer 39, corresponding to conveyers 19 and 33, has its runs 40 and 41 in vertical alinement with the runs 26, 21, 35 and 34. These conveyers 36 and 39 provide service in both directions between the fifth, sixth and seventh floors.

By reason of the arrangement of runs shown the ascending and descending runs between the adjacent levels are arranged side by side, and between successive levels the ascending runs are arranged alternately in vertical alinement and the descending runs are correspondingly arranged alternately in vertical alinement. For example, in the present embodiment of the invention, between the first and second floors the ascending run 10 is located at one side of the descending run 26 or they are in parallel vertical planes, while between the second and third floors the ascending run 21 is located at the opposite side of the descending run 15, so that the runs 10 and 15 are in one vertical plane and the runs 26 and 21 are in another vertical plane preferably parallel to the first. This arrangement continues throughout the system, so that the alternate up and down runs are aligned vertically although moving in opposite directions; thus the runs 10, 15, 30, 31, etc., are on one side and the runs 26, 21, 35, 34, etc., are on the other side of a common median line while the runs on either side move alternately in opposite directions, as runs 10 and 30 travel oppositely to 15 and 31, and runs 26 and 35 travel oppositely to 21 and 34. By this arrangement the exit from each run of either series or side is located adja-

cent to the entrance of the succeeding run, and this is true when the passenger is traveling either up or down.

Referring to Fig. 2, which shows the arrangement at the second floor, the exit 11 of the ascending run 10 is adjacent and opposite the entrance 20 of the next ascending run 21, and at the other end the exit 16 of the descending run 15 is adjacent or opposite the entrance 25 of next descending run 26. The same relative arrangement of entrances and exits continues throughout the system, so that the passenger is enabled when traveling in either direction to step from the exit landing of one run to the entrance landing of the next succeeding run. The successive landings of the ascending and descending runs are arranged opposite to each other or in associated pairs.

The landings may be provided with shunts 42 of any suitable character, and hand-rails 43 and balustrades may also be employed.

Having described my invention what I claim is—

1. A device of the class described, such as a moving foot-way, providing successive oppositely moving transporting runs respectively connecting different pairs of levels.

2. A device of the class described, such as a moving foot-way, providing successive oppositely moving transporting runs respectively connecting different pairs of levels, each run having a landing at each of the levels connected thereby.

3. A device of the class described, such as a moving foot-way, providing successive ascending and descending transporting runs, each run connecting a different pair of levels.

4. A device of the class described, such as a moving foot-way, providing straight ascending and descending transporting runs between more than two levels, each run having a landing at each of the levels between which it extends.

5. A device of the class described, such as a moving foot-way, providing ascending and descending transporting runs successively extending between different pairs of levels and each run having a landing at a common level.

6. A continuous conveyer providing a moving transporting run between two levels and an oppositely moving successive transporting run between one of such levels and another level.

7. A continuous conveyer providing successive oppositely moving transporting runs between different levels and an intermediate level.

8. A continuous conveyer providing successive oppositely moving transporting runs between different levels and an intermediate level, each of said runs having a landing at the intermediate level.

9. A continuous conveyer providing suc-

cessive oppositely moving transporting runs between different levels and an intermediate level, each run having a landing at the intermediate level and also a landing at the other level with which it is associated.

10. A moving foot-way having duplex transporting runs successively moving in opposite directions between different pairs of consecutive levels.

11. A continuous conveyer having vertically aligned oppositely moving transporting runs connecting different levels with an intermediate level.

12. A conveyer having oppositely moving straight runs connecting an intermediate level with respect to upper and lower levels and adapted to transport to such intermediate level on both runs.

13. A conveyer having oppositely moving straight runs connecting an intermediate level with respect to upper and lower levels and adapted to transport from such intermediate level on both runs.

14. A continuous conveyer having vertically aligned oppositely moving transporting runs connecting different levels with an intermediate level, each run having a landing at the intermediate level and also at its other associated level, and end carriages between successive levels through which the conveyer passes.

15. A pair of inclined moving conveyers connecting an intermediate level with respect to upper and lower levels, one of such conveyers being adapted to transport to such intermediate level on both runs and the other to transport from such intermediate level on both runs.

16. A pair of duplex conveyers connecting an intermediate level with respect to upper and lower levels and having oppositely moving runs, one of such conveyers being adapted to transport to such intermediate level on both runs and the other to transport from such intermediate level on both runs.

17. In a device of the class described, a pair of conveyers, each conveyer providing oppositely moving transporting runs between successive pairs of levels and with the associated conveyer providing oppositely moving runs between adjacent levels.

18. In a device of the class described, a pair of conveyers, each conveyer providing oppositely moving transporting runs between different levels and an intermediate level and with the associated conveyer providing oppositely moving runs between adjacent levels, each run having a landing at the intermediate level opposite to the landing of the similarly moving run of the other conveyer.

19. In a device of the class described, a pair of conveyers, each conveyer providing oppositely moving transporting runs between different levels and an intermediate

- level and with the associated conveyer providing oppositely moving runs between successive levels, each run having a landing at the intermediate level opposite to the landing of the similarly moving run of the conveyer and also a landing at the other level with which such run connects. 5 and arranged side by side, the exit and entrance landings of each similarly moving series being opposite. 60
20. In a device of the class described, a pair of oppositely arranged conveyers, each 10 conveyer providing vertically alined oppositely moving transporting runs between different levels and an intermediate level and with the other conveyer providing oppositely moving runs between successive 15 pairs of levels. 65
21. A device of the class described, comprising a plurality of duplex conveyers in which each conveyer provides oppositely moving transporting runs between successive 20 pairs of levels and each pair provides ascending and descending runs between adjacent levels. 70
22. In a device of the class described, a series of moving foot-ways providing ascending and descending runs between different levels, the alternate runs being in vertical alinement. 75
23. In a device of the class described, a series of moving foot-ways providing ascending and descending runs between different levels, the ascending run to one level being in vertical alinement with the descending run to such level. 80
24. In a device of the class described, a series of moving foot-ways providing ascending and descending runs between successive levels, the runs between similar levels being arranged side by side and the runs between successive levels alternating from side 40 to side. 85
25. In a device of the class described, ascending and descending moving foot-ways providing runs arranged side by side in pairs between successive levels, the runs to successive levels being arranged on alternate sides of each other. 90
26. In a device of the class described, a series of ascending moving foot-ways providing runs to successive levels in zig-zag 50 formation, and a similar series of descending moving foot-ways providing runs between the same levels, the runs between similar levels being side by side and arranged on alternate sides of each other between successive levels. 95
27. In a device of the class described, a series of ascending and descending moving foot-ways providing straight runs moving in opposite directions between similar levels. 100
28. In a device of the class described, a series of ascending and a series of descending moving foot-ways providing straight runs, the exit of each run of each series being opposite to the entrance of the succeeding run of such series. 105
29. In a device of the class described, a series of ascending and a series of descending moving foot-ways providing straight runs, the exits and entrances of succeeding runs of each series being at the adjacent ends of the runs of such series. 110
30. In a device of the class described, a series of ascending and a series of descending moving foot-ways providing runs between successive levels, and providing both an ascending and a descending run between the same levels, the ascending run to one level being in the same vertical plane as the descending run to such level, the runs between similar levels being side by side and arranged on alternate sides of each other between successive levels, the exit of each run of each series being opposite to the entrance of the succeeding run of such series. 115
31. In a device of the class described, a series of moving foot-ways providing oppositely arranged runs, the alternate runs being on the same side. 90
32. In a device of the class described, a series of moving foot-ways providing runs arranged on opposite sides of a median line, the alternate runs being on the same side 95 thereof.
33. In a device of the class described, a series of moving foot-ways providing runs arranged on opposite sides of a median line, the runs on either side moving alternately in opposite directions. 100
34. In a device of the class described, a series of moving foot-ways providing runs arranged on opposite sides of a median line, the exit of one run being opposite to the entrance of the next succeeding run. 105
35. In a device of the class described, a series of moving foot-ways providing runs having their landings arranged in pairs, the exit and entrance landings of each pair being at the same ends of their associated runs. 110
- In testimony whereof I affix my signature in presence of two witnesses.
